CLAIM

The ornamental design for a lighted cap for a squeeze tube, substantially shown and described.

DESCRIPTION

FIG. 1 is a top, front, left side, perspective view of the lighted cap for a squeeze tube, showing my new design; FIG. 2 is another perspective view of the lighted cap for a squeeze tube;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof, and,

FIG. 8 is a right side elevational view thereof.

The oblique shade lines in the drawings describe transparent areas of the lighted cap for a squeeze tube.

The broken line show in FIGS. 1, 2 and 4 depict portions of the lighted cap for a squeeze tube which form no part of the claimed design.
